UNITED STATES PATENT OFFICE.

LEONARD G. GRAY AND ARTHUR J. BLYTH, OF DECATUR, ILLINOIS, ASSIGNEES TO WALRUS MANUFACTURING COMPANY, OF DECATUR, ILLINOIS, A CORPORATION OF ILLINOIS.

DESIGN FOR A LUNCHEONETTE-BUFFET.

47,462.

Specification for Design.

Patented June 15, 1915.

Application filed April 16, 1915. Serial No. 21,930. Term of patent 3½ years.

To all whom it may concern:

Be it known that we, LEONARD G. GRAY and ARTHUR J. BLYTH, citizens of the United States, residing at Decatur, in the county of Macon and State of Illinois, have invented a new, original, and ornamental Design for Luncheonette-Buffets, of which the following is a specification, reference being had to the accompanying drawing, forming part thereof, in which the figure is a perspective view of a luncheonette buffet, showing our new design.

We claim:

The ornamental design for a luncheonette buffet, as shown.

LEONARD G. GRAY.
ARTHUR J. BLYTH.
